UNITED STATES PATENT OFFICE

2,545,391

DUAL SOCKET WRENCH WITH SEPARATE ACTUATORS

Robert E. Stanton, Denver, Colo.

Application January 24, 1949, Serial No. 72,333

6 Claims. (Cl. 81—53)

1

This invention relates to wrenches and more particularly to a wrench for opening and closing "Nordstrom" high pressure valves used in the petroleum industry.

The valves alone referred to are of the plug type, a tapered, rotatable, ported plug being employed in a tapered valve body. One end of the plug is provided with a square head for receiving a suitable wrench and this head also carries a screw rotatable relative thereto, which, when rotated, forces lubricant to the valve plug and seat which lubricates and frees the plug so that it may be turned in the valve body. In the prior art, a second wrench is employed to rotate this screw.

The principal object of the invention is to provide a single wrench which will rotate a valve of the class referred to and also force lubricant to it.

Another object is to provide a wrench which will continually supply lubricant to the valve until the valve becomes sufficiently lubricated to turn in response to a predetermined torque applied thereto.

Further objects are to provide a wrench which is simple and rugged in construction, economically manufactured, and automatic in its operation of lubricating a valve.

Still further objects and salient features will become more apparent from a consideration of the description to follow, the appended claims, and the accompanying drawing in which:

Figure 1 is a top plan view of the wrench, a portion being broken away to show a detail thereof;

Figure 2 is a side elevation, a portion thereof as taken on line 2—2, Figure 1, being shown in section;

Figure 3 is a section taken on line 3—3, Figure 1, showing the wrench in operative position on a valve, the latter being shown partially in section;

Figure 4 is a section taken on line 4—4, Figure 3; and

Figure 5 is a section taken on line 5—5, Figure 1.

Referring to the drawing, there is shown in Figure 4, a valve 10, of the type referred to, having a tapered bore therein and a tapered plug or gate 11 seated in the bore. This plug has an external square head 12 which, in the prior art, is turned by a suitable box wrench having a square opening therein. The head also threadedly carries a screw 13, which, when turned, forces lubricant from lubricant chamber 14 to the surface of the plug through suitable passages 15, 16, 17.

2

In the prior art this screw is turned by a separate wrench applied to head 18 of the screw. The valve just described is conventional and well known and forms no part of the invention per se, hence has been illustrated in simplified form.

The wrench which is the subject-matter of the invention has a body portion 20 having a square socket 21 at one end thereof which fits the square head on the valve. The other end has an integral laterally extending arm 22 and a plate 23 secured to such arm as by screws 24 to form a rectangular slot 25, as best shown in Figure 5.

The outside of socket 21 is machined circular as shown at 26, best shown in Figure 4, and a wrench handle 27 having a circular eye 28 surrounds the circular portion or flange, the eye being rotatable thereon. An intermediate portion of the wrench handle passes through slot 25 and in a position of nonuse the handle abuts a portion 29 formed on body 20, being resiliently held thereagainst by a spring 30. A second portion 31 formed on body 20 carries an adjusting screw 32 which has a shouldered head 33 which abuts one end of the spring. The shouldered screw, and a projection 34 on handle 27, retain the spring in place in slot 25.

The circular flange 26, previously described, also has rotatably mounted thereon a cup-shaped ratchet member 35 having ratchet teeth 36 circumferentially disposed thereon. The ratchet member has a hub 37 on one side into which fits a sleeve 38 having a hexagonal socket opening 39 therein which is constructed to fit the head 18 of screw 13. This sleeve has a flange 40 at its lower end and pins 41 secure the socket sleeve to hub 37. This manner of securing the various parts together is exemplary only and it is apparent that sleeve 38 and hub 37 may be secured together by a spline connection, welding, or in any other suitable manner.

Handle 27 has an upstanding boss 42 having a square opening therein in which is slidably mounted a ratchet pawl 43 which is urged against the ratchet teeth 36 by a suitable spring 44, as shown in Figure 3.

In operation the wrench is placed on the square head of the valve, as shown in Figure 3, and the handle is rotated in a direction to compress the spring 30. If the valve plug is relatively free in its seat the spring will be compressed a certain amount and the valve plug will then turn. While compressing the spring the ratchet pawl also rotates the ratchet and the lubricant feed screw a slight amount, forcing lubricant to the valve. 55 If the valve plug fails to turn, because it is stick-

ing in its seat, the handle is released. During release the ratchet pawl is positioned in another ratchet tooth. The wrench handle is again pulled, forcing more lubricant to the valve. This process of pulling and releasing the handle is continued until sufficient lubricant is forced into the valve to free it, at which point the valve plug will rotate in response to the force applied through the spring. Any desired tension on the spring may be obtained by suitable adjustment of screw 32.

While the use of spring 30 has the advantage that it will give the wrench a springy "feel" in turning the valve plug and the valve plug will release under application of a predetermined torque resiliently applied, the spring is not indispensable for operation. The slot 25, in effect, provides a lost motion connection between the body 20 and handle 27 and if the spring were omitted projection 34 would abut screw 33 and still turn the valve. If it failed to turn, handle 27 could still be oscillated in the slot to force lubricant to the valve plug.

While a single embodiment has been shown by way of exemplification, it will now become apparent that many modifications are possible within the spirit of the invention. The ratchet, for example, need not necessarily have teeth since the well known overrunning toothless type of intermittent clutch could be employed, if desired. While the sockets for the valve head and lubricant screw have been shown as square and hexagonal, respectively, these could be any shape desired to fit the respective parts with which they cooperate. If it be desired to turn a valve without applying lubricant, the wrench may be used with the ratchet pawl released, such as by releasing it with a ratchet release 45, which could be retained in released position in any suitable manner.

Another manner of turning the valve plug without forcing lubricant thereto is by merely turning the wrench handle in a direction reverse to that described. It is apparent that when so used handle 27 will engage abutment 29 and as the valve is turned the ratchet pawl will pass over the ratchet teeth without rotating the lubricant screw. It thus becomes apparent that in the event the valve or valves to be operated are well lubricated, as would be the case where they are frequently used, the wrench may be used to turn the valves without forcing lubricant thereto.

Many other modifications will become apparent within the spirit and scope of the invention, hence the invention is not to be limited except as defined by the appended claims.

Having described the invention what is claimed as new is:

1. A wrench for turning the operating head of a valve and a lubricant forcing screw disposed axially therein, comprising, socket means engageable with the head, socket means engageable with the screw, a member rigidly connected to the first socket means extending laterally thereof, a ratchet wheel rigidly connected to the second socket means, a handle overlying said member and rotatable relative thereto, a lost motion connection between the handle and member, and a ratchet pawl carried by the handle engageable with the ratchet wheel.

2. A wrench in accordance with claim 1 wherein the lost motion connection is at the end of said member.

3. A wrench for turning the operating head of a valve having a lubricant forcing screw disposed

axially therein, comprising, socket means engageable with the head, socket means engageable with the screw, a circular surface on the outside of the first socket means, a handle having a circular opening at one end thereof surrounding the circular surface, a ratchet wheel secured to the second socket means also rotatably supported on said surface, means associated with the first and second socket means for holding the two socket means and handle means together, a ratchet pawl on the handle engageable with the ratchet wheel, an integral member extending laterally of the first socket means on which the handle overlies, and means at the end of the member permitting limited movement of the handle relative thereto, the construction being such that oscillation of the handle within the limit rotates the screw to feed lubricant to the screw and movement of the handle after it reaches the limit rotates the valve.

4. In a valve of the type having a rotatable valve member with means for operating it and means for forcing lubricant thereto, the combination therewith of a wrench for operating the two means aforesaid, said wrench comprising, means engaging the valve operating means, means engaging the lubricant forcing means, a single handle for operating the last two means, the wrench having operative connections between the handle and the last two means such that movement of the handle in one manner operates the lubricant forcing means only and movement of the handle in another manner operates the valve operating means.

5. A unitary wrench for turning two concentric wrench operated members rotatable relative to one another about a common axis, comprising; means carried by the wrench adapted to grip one member and rotate same, means carried by the wrench adapted to grip the other member and rotate same, a handle carried by the wrench operatively connected to both means, the handle and both means all being relatively rotatable about a common axis, intermittent gripping means operatively interposed between the handle and one means, and abutment means interposed between the handle and the other means adapted to limit rotation of the handle relative to the other means, whereby the latter may be rotated after the handle is relatively rotated a predetermined amount.

6. In a valve unit of the type having first and second wrench operated members rotatable relative to one another about a common axis, the first member being adapted to rotate a rotary valve carried by the unit between open and closed positions, and the second member being adapted to force lubricant to the rotary valve, upon relative rotation between it and the valve, comprising; wrench means for operating said members, said wrench means including, first gripping means adapted to grip the first member, second gripping means adapted to grip the second member, handle means connected to the first gripping means, and operative connections including the handle means and an intermittent gripping device constructed and arranged so that oscillatory movement of the handle means will intermittently rotate the second member to force lubricant to the valve, and swinging movement of the handle through a predetermined arc will move the valve between open and closed positions.
